UNITED STATES PATENT OFFICE.

FRED A. LUNDAHL, OF MOLINE, ILLINOIS.

FENDER-BENDING MACHINE.

1,296,199.

Specification of Letters Patent.

Patented Mar. 4, 1919.

Application filed September 6, 1917. Serial No. 190,023.

To all whom it may concern:

Be it known that I, FRED A. LUNDAHL, a citizen of the United States, residing at Moline, in the county of Rock Island and State 5 of Illinois, have invented certain new and useful Improvements in Fender-Bending Machines, of which the following is a specification.

My invention has reference to fender bending machines, and pertains more specially to devices for forming the sheet-metal fenders which are used to form a guard for the wheels of automobiles and similar vehicles. Such fenders are provided with a 15 double curvature, one longitudinally of the shield and the other transversely thereof, and it is customary to give the desired form to the fender while the metal is in a cold or unheated condition. On this account it is 20 necessary to give the fender its longitudinal curvature by a succession of operations, resulting in a gradual reduction thereof to the desired shape, to prevent undue tension or stretching of the material, which would tend 25 to break or distort the fibers thereof. The present invention has to do largely with means for producing the desired amount of curvature of the metal, by gradually increasing the degree of curvature thereof.

In the drawings: Figure 1 shows a machine embodying my invention in front elevation, with some of the parts omitted to more clearly exemplify other parts thereof. Fig. 2 is a vertical section on the line α — α 35 of Fig. 1. Fig. 3 is a vertical section on the line y — y of Fig. 1. Fig. 4 is a plan view of my invention with some of the parts broken away. Figs. 5 and 6 are diagrammatic views of the forming devices in different positions.

Similar parts are indicated by corresponding reference characters throughout the several figures.

The frame of the machine consists of side 45 pieces 1 and 2, supported on an I-beam base 3. Each of the side-pieces is provided with a vertical recess 4, in the bottom of which is a boxing 5 in which is rotatably mounted the end of a shaft 6. Centrally of

the machine there is fixed on said shaft a 50 concave roll 7, having annular flanges 8. Above the boxing 5 is supported a boxing 9 in which is journalized a shaft 10, similar to the shaft 6, and provided with a roll 11, having a convex face adapted to coöperate with the 55 roll 7 to give to a metal fender the desired amount of curve, transversely thereof.

Journalized in the top of the frame is a main drive shaft 12, on which is loosely supported a pair of pulleys 13 and 14, to which movement is imparted in any known manner to cause a continuous rotation thereof in opposite directions. Fixed to the shaft 12 is a pair of sleeves 15 and 16 adapted to be operatively connected with the pulleys 13 and 14 by means of friction devices 17 and 18 engaging drums 19 and 20 rigidly connected with said pulleys. Slidable on the shaft 12 is a pair of collars 21 and 22 provided with arms 23 and 24 having a connection with the friction devices and capable of actuating the same when the collars are moved outwardly on the shaft. Such friction devices and operating means therefor may be of a conventional pattern, and nothing is 75 herein claimed broadly thereon.

Projected between the collars 21 and 22 is an arm 25 secured at its forward end to a shift-bar 26 slidably mounted on the top of the machine, and provided with an arm 27 80 extending to the side of the machine, and designed to be connected up with suitable hand or foot mechanism for moving the bar 26 in either direction, at will. The movement of such shift-bar in one direction will 85 cause the arm 25 to move one of the collars 21 or 22 outwardly, throwing the shaft into engagement with the corresponding pulley 13 or 14, and imparting to the shaft a rotary movement similar to that of the pulley with 90 which it is connected. A movement of the shift-bar in the opposite direction has a contrary effect, causing a rotation of the shaft in the opposite direction.

On one end of the shaft 12 is a gear wheel 95 28, in mesh with an idler gear-wheel 29 on a shaft 30, the wheel 29 being in mesh with a gear-wheel 31 on one end of the shaft

10. A rotary movement of the shaft 12 may thus be imparted to the shaft 10, to cause a rotation thereof similar to that of the shaft 12. On the opposite end 5 of the shaft 12 is a gear-pinion 32 communicating by means of a pair of idler gear-wheels 33 and 34 with a gear-wheel 35 on one end of the shaft 6. Movement of the shaft 12 is thus imparted to the shaft 6 to 10 cause a rotation thereof opposite to that of the shaft 10.

Supported in front of the machine is a feed-table 36, along which the sheet metal plates from which the fenders are formed 15 are moved in the direction of the rolls 7 and 11, the fenders being at this time in the form of flat plates, with upwardly turned flanges on their edges. The table 36 is provided with upwardly turned edges 20 37 by means of which the metal plate is guided into the rolls. The flanges 8 continue the guidance of such plate in a straight line.

On the inner faces of the side-plates 1 25 and 2 are secured ways 38, in inclined position, in which ways are slidably held blocks 39, in which are secured the ends of a cross-shaft 40. 41 is a chute of modified wedge form, supported on the shaft 40 by 30 means of a block 42 mounted on the shaft and attached to said chute. The upper face of the chute is concaved to conform with the curvature of the rolls 7 and 11, whereby said chute is adapted to receive a plate 35 which has been passed through the rolls. The sharp edge of the chute 41 rests normally on the roll 7 at a point in rear of a vertical line passing medially of said roll. In the rear ends of the ways 38 are cross- 40 heads 43, perforated to permit the passage of rods 44, fixed to the blocks 39, and provided on their rear ends with rollers 45. Said rollers are engaged by eccentrics 46 45 on a shaft 47 journaled in bearings 48 fixed to the side-pieces 1 and 2. Rotation of such shaft causes the eccentrics thereon to move the rods 44 upwardly, elevating the rear end of the chute 41, for the purpose hereinafter more fully set forth.

50. On one end of the shaft 47 is a gear-pinion 49 engaged by a gear-rack 50 slideable in a bearing 51 secured to the frame of the machine. Fixed to the side-piece 2, near the front thereof, is a bracket 52, on 55 which is fulcrumed a bell-crank lever 53, the short arm of which is connected by means of a rod 54 with the rack 50. A segment 55 is provided with a series of teeth 56, engaged by a spring-controlled 60 pawl 57 pivoted to the lever 53 convenient to the handle 58 thereof. When the operator moves such handle inwardly the pawl 57 slips over the teeth 56, engaging the one

at which it is stopped. This operates to move the rack 50 forwardly, turning the eccentrics 46 and moving the blocks 38 upwardly and forwardly. This movement is accompanied by a corresponding movement of the shaft 40 and rear end of the chute, operating to give a sharper curve to the 65 fender, as indicated in Figs. 5 and 6, the fender being represented therein by the broken lines. In Fig. 5 the chute is shown in a substantially horizontal position, so that the fender only comes in contact with 70 the rear part of the chute. In Fig. 6 the rear edge of the chute has been raised, and this movement has been accompanied by a movement of the forward edge of the chute upwardly along the face of the roll 7, so 75 that the fender traverses the entire face of the chute, receiving a greater degree of curvature therefrom.

After the metal sheet has been first operated on, so as to be given a slight amount 80 of curve, the movement of the machine is reversed by action of the shift-bar 26, and the plate is returned forwardly through the rolls. Coincidentally with this forward movement the shaft 47 is rotated sufficiently 90 to partially raise the chute 41, whereupon the movement of the machine is again reversed and the plate again operated in a rearward direction, giving an additional 95 bend thereto. This operation is continued until the desired curvature of the plate is attained. In each succeeding operation the lever 53 is moved a little farther inwardly, the pawl 57 passing over one or more additional teeth at each succeeding movement. 100 The operator soon becomes skilled in the operation of the machine, and is able to determine the amount of additional elevation to be given to the chute 41 for each operation. If desired the teeth 56 can be 105 numbered or otherwise indicated by suitable marks, so as to assist in the proper operation of the lever.

The short arm of the lever 53 is provided with a series of openings 59, for adjustment of the end of the rod 54, to give the rack 50 a greater or less movement, as desired.

What I claim as my invention, and desire to secure by Letters Patent of the 115 United States, is:

A device of the class described, comprising a frame; a pair of rolls co-operatively mounted therein and adapted to impart to a sheet of metal a desired amount of curvature transversely thereof; a pair of blocks slidably movable at opposite sides of said frame so as to move inwardly and upwardly or the reverse; a shaft supported in said blocks; a forming member supported by 120 said shaft and having one of its edges slid- 125

ably held on one of said rolls; a shaft rockingly mounted in said frame; a pair of eccentrics on said shaft operatively connected with said blocks to impart a sliding movement thereto; means for suitably actuating said rock-shaft; means for rotating said rolls in opposite directions; means for reversing the rotation thereof; and means for

directing a sheet of metal to said rolls at a right angle thereto.

In testimony whereof I affix my signature in the presence of two witnesses.

FRED A. LUNDAHL.
